Primary Examiner — Cathron C Brooks*Assistant Examiner* — Christian P. McLean(74) Attorney, Agent, or Firm — Egbert, McDaniel & Swartz, PLLC(57) CLAIM

The ornamental design for a glass jar, as shown and described.

DESCRIPTION

FIG. 1 is an upper perspective view of a glass jar showing my new design.

FIG. 2 is a side view thereof;

FIG. 3 is an opposite side view thereof;

FIG. 4 is a front view thereof;

FIG. 5 is a rear view thereof;

FIG. 6 is a top view thereof; and,

FIG. 7 is a bottom view thereof.

The broken lines illustrate portions of the glass jar that form no part of the claimed design.
